(57) **CLAIM**

The ornamental design for a modular cooking oven, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of the oven according to my new design;

FIG. 2 is a left side view thereof;

FIG. 3 is a right side view thereof;

FIG. 4 is a top perspective view thereof in an alternate configuration;

FIG. 5 is a top perspective view of the oven of FIG. 1;

FIG. 6 is a front view of the oven according to a second embodiment;

FIG. 7 is a left side view thereof;

FIG. 8 is a right side view thereof;

FIG. 9 is a top perspective view thereof in an alternate configuration;

FIG. 10 is a top perspective view of the oven of FIG. 6;

FIG. 11 is a front view of the oven according to a third embodiment;

FIG. 12 is a left side view thereof;

FIG. 13 is a right side view thereof;

FIG. 14 is a top perspective view thereof in an alternate configuration;

FIG. 15 is a top perspective view of the oven of FIG. 11;

FIG. 16 is a front view of the oven according to a fourth embodiment;

FIG. 17 is a left side view thereof;

FIG. 18 is a right side view thereof;

FIG. 19 is a top perspective view thereof in an alternate configuration; and,

FIG. 20 is a top perspective view of the oven of FIG. 16. The broken line depictions illustrate unclaimed portions of the modular cooking oven.

The areas of solid gray represent contrasting light and dark color tones.
